UNITED STATES PATENT OFFICE.

ROBERT H. KIRBY, OF ST. LOUIS, MISSOURI.

WASHING MACHINE FOR LIGHT HOUSEHOLD SERVICE.

Application filed January 16, 1922. Serial No. 529,436.

To all whom it may concern:

Be it known that I, ROBERT H. KIRBY, a citizen of the United States, and a resident of the city of St. Louis, in the county of St. Louis and State of Missouri, have invented certain new and useful Improvements in a Washing Machine for Light Household Service; and I do hereby declare that the following is a full, clear, and exact 10 description of the same, reference being had to the accompanying drawings, and to the numerals of reference marked thereon, which form a part of this specification.

This invention relates to a machine primarily designed for washing clothes, but also susceptible for use in churning butter.

And it is an object of this invention to provide a small washing machine of novel structure designed for washing dainty garments, wearing apparel, small household linen, and any other special clothing or household fabrics that are not too bulky.

It is a further object of this invention to provide such a washing machine that can be readily handled as a unit by a person, so that the same can be readily placed upon and removed from a heating apparatus to which the washing receptacle is adapted.

It is a further object of this invention to construct a washing machine that is adapted for churning butter or the like.

It is also an object of this invention to provide such a washing machine with a novel form of transmission mechanism neatly enclosed and operated by a small electric motor or other prime mover.

With these and other objects in view, which will become more apparent from the following description and disclosure in the drawings, this invention comprises the novel mechanisms, structures and combinations hereinafter described and more particularly pointed out in the appended claim.

In the accompanying drawings, which illustrate a preferred embodiment of this invention, and in which similar reference numerals refer to similar features in the different views:

Figure 1 is a side elevational view of my washing machine mounted upon an electric heater.

Figure 2 is a top plan view of the same.

Figure 3 is a top plan view of the heating element on a slightly enlarged scale.

Figure 4 is a section on the line 4-4 of Figure 2 on an enlarged scale.

Figure 5 is a fragmentary enlarged section illustrating the manner of connecting the transmission mechanism to the plunger rod.

Figure 6 is a rear view of the switch board and wiring on the electric heater.

Figure 7 is an enlarged section through the transmission casing illustrating the gearing transmission.

Figure 8 is an enlarged sectional view through the flexible connecting means between the motor and transmission gearing.

Figure 9 is an enlarged view taken on the line 9-9 of Figure 1, showing the bottom of the heating element in plan view and the supporting legs in section.

My invention in its broadest aspect comprises a washing receptacle in which the clothes are put, and a member for closing the receptacle, a washing element extending through said member, and operating mechanism including a motor supported on said member and operatively connected to said washing element. This mechanism supporting member is adapted to be removably applied to the washing receptacle and may constitute the cover thereof.

As shown on the drawings:

In referring to the different figures of the drawing, especially Figure 4, it will be noted that I have illustrated a washing receptacle 1 having an upwardly dished bottom 2 and a mechanism supporting member in the form of a cover 3 which has a downwardly extending annular flange 4 provided with a bead 5 which is designed to abut against a bead 6 forming the upper edge of the receptacle 1, when the flange 4 has been inserted within the upper end of the receptacle. The cover thus is frictionally held in position sufficiently tight to prevent leakage from splashing, but if the machine is overloaded with clothes, the cover may be lifted from its position when the plunger reaches the lowest point of its stroke, thus protecting the motor from strain and from being burned out. The lifting of the cover under such circumstances will also cause a noise that will warn the operator.

The cover 4, which forms the supporting means for the operating mechanism of the washing machine, can be readily removed by a person without much effort when it is not desired to wash garments in the machine, and the receptacle can be used for other purposes. Further, the combined receptacle

and operating mechanism can be readily removed from the heating apparatus which is also adapted for cooking purposes. To this end, my improved washing machine lends 5 itself admirably to household service where space is limited and possesses numerous advantages over the larger machines on the market that cannot be thuswise dismantled and are not adapted for use in apartments 10 affording only limited space.

The operating mechanism comprises a small electric motor 7 (Figures 1 and 2) supported upon a base member 8 on the cover, the base member 8 being provided 15 with a switch for starting and stopping the motor when the current is turned on, and for regulating the speed of the machine. The armature shaft 9 (Figures 2 and 8) has secured upon its end a collar 10, to which 20 one end of a flexible connecting means such as a coil spring 11 is secured, the opposite end of said spring being connected to a collar 12 rigidly secured on the transmission shaft 13 which projects a short distance 25 from the transmission housing or casing 14 (Figure 4) mounted upon the cover 3 and secured by a bracket 14^a secured to the cover.

The shaft 13 is journalled in bearings formed in the walls of the casing 14 (Figure 30 4) and has secured thereon a small drive pinion 15 (Figure 7) within the casing, which meshes with a gear wheel 16 secured upon a shaft 17 also journalled in the walls 35 of the casing. A small pinion 18, shown in dotted lines in Figure 7, is secured upon the shaft 17 and meshes with a gear wheel 19 secured upon a shaft 20 journalled in the walls of the transmission casing. The housing or casing 14 is provided with a partition 40 wall 21 (Figure 5) which comprises one of the walls in which the shaft 20 is journalled. The shaft 20 projects beyond the partition wall where it rigidly supports a crank 22 having a crank pin 23 secured on its outer 45 end.

The partition wall 21 divides the transmission housing into two compartments; one compartment encloses the gearing; the other compartment houses the reciprocating 50 plunger rod. In this way it becomes impossible for any dirt, grease or lubricant to find its way from the driving gears to the washing receptacle. The second compartment comprises a downwardly extending base portion 24 resting upon the cover and provided with an aperture through which the plunger rod 26 is adapted to be reciprocated. The upper part 14^a of the housing or casing 14 is removably secured to the lower 55 part by screws or the like, and the second compartment is closed by a removable vertical cover plate 14^b (Figure 1). Thus the gearing and operating mechanism connected to the plunger rod is completely enclosed 60 and protected in its use from water and for

safety of the operator, and when not in use from breakage and rust and causing injury to individuals.

The upper part 14^a of the housing is provided with an upwardly directed extension 70 14^c which supports a depending rod 25 which serves as a guide for the aforementioned reciprocating plunger rod 26, which is a hollow tubular shaft that telescopes over the guide rod 25 and extends through the 75 aperture in the base 24 of the housing and through a suitable aperture in the cover 3 of the washing receptacle to a suitable depth in said receptacle for supporting the washing element which may be in the form of a 80 vacuum cup or pounder 27.

The upper end of the plunger rod 26 has affixed thereon a wrist pin block 28 having a wrist pin 29 upon which is journalled the upper end of a pitman 30, the lower end of 85 which is journalled upon the pin 23 on the crank 22. The wall of the extension 14^c adjacent the wrist pin 29 is provided with a guide groove 31 (Figure 5) in which the outer end of the pin 29 is guided in a true 90 rectilinear path. The hubs of the pitman 30 may be provided with grease cups 32 for the purpose of furnishing lubricant to the respective crank pins.

It is characteristic of my invention that 95 the cover with the operating mechanism thereon may be removed and inverted, the vacuum cup removed, and the inverted mechanism placed within the receptacle 1 for shipping purposes, or for storing and 100 handling the same.

The washing receptacle 1 may be heated by placing the same upon a stove or other heating apparatus of suitable form. In the present instance there is illustrated an electric heater 33 of suitable construction. The illustrated electric heater consists of a variable resistance box 33^a supported upon legs 34 in any approved manner, the resistance box being covered with a grate 35 for more 105 effectively radiating the heat from the coils. In order to increase or decrease the resistance of the coils, a switch 36 (Figure 1) has been provided on the side of the coil box whereby coils can be cut out or put in the 110 electric circuit. As the structure of the resistance box and switch are well known, no detailed description is necessary.

The current for the heater and motor can be derived from the electric lighting system and conveyed by the conductor 37 to the coil box and from the coil box through the conductor 38 to the motor which is supplied with a control switch, so that the motor need not run while the water in the washing receptacle is being heated, or so it can be operated when the electric heater is not being used.

When it is desired to use the washing machine with the stand furnished, it is only 130

necessary to place the same upon the heater and connect the heater with the source of energy and regulate the switch 36 in accordance with the heat desired. Assuming that a quantity of washing fluid and clothes have been placed in the receptacle 1, it will be evident that the heat radiating from the coils will soon heat the washing fluid. When the washing fluid has been sufficiently heated, 10 the motor 7 can be put in operation by means of the motor switch. The operation of the motor will put in operation the train of gears 15, 16, 18 and 19, whereby the shaft 20 and crank 22 are rotated for reciprocating the plunger rod 26 as is obvious from the drawings.

It will accordingly be apparent that I have invented a washing machine adapted for light household service that occupies but 20 little space and can be readily kept in a small apartment. It should be noted that a single member supports the entire operating mechanism, which is completely housed in a compact form, and that the member and mechanism can be readily removed so that the same can be readily stored on a shelf or the like when not in use.

I am aware that numerous details of construction may be varied through a wide

range without departing from the principles of this invention, and I therefore do not purpose limiting the patent granted otherwise than necessitated by the prior art.

I claim as my invention:

In a device of the class described, a support, a casing mounted thereon, an intermediate vertical partition therein dividing the same into two compartments, gearing in one compartment embodying a rotatable shaft extending through a bearing in said partition into the other compartment, a motor on said support connected to said gearing, a vertical extension forming part of said second compartment, a depending guide rod in said extension, a hollow plunger rod 45 in said second compartment mounted to reciprocate on said guide rod, and a crank and pitman connection between said rotatable shaft and plunger rod for reciprocating the latter on its guide rod.

In testimony whereof I have hereunto subscribed my name in the presence of two subscribing witnesses.

ROBERT H. KIRBY.
